UNITED STATES PATENT OFFICE

VICTOR AUGUSTE MARIE ERNEST BRAHY, OF ST. HILAIRE, QUEBEC, CANADA

AIRSHIP CONSTRUCTION

Application filed January 17, 1929. Serial No. 333,111.

The invention relates to airship construction, as described in the present specification and illustrated in the accompanying drawings that form part of the same.

The invention consists essentially of the novel features of construction pointed out broadly and specifically in the claims for novelty following a description containing an explanation in detail of an acceptable form 10 of the invention.

The objects of the invention are to utilize the wind and air currents to the fullest advantage in stabilizing, poising, and propelling flying machines; to obtain good results 15 from a particular arrangement of wind rotors, whereby in the rotation of these rotors in the several planes, the movement of the air is both deflected and turned to account in the operation of the machine; to insure buoyancy without any great expanse of wing and 20 generally to provide in flying machines a reliable swift and durable type of ship.

In the drawings Figure 1 is a front elevational view of a flying machine of the air- 25 plane type.

Figure 2 is a plan view of the machine illustrated in Figure 1.

Figure 3 is an elevational view of the machine.

Figure 4 is a cross sectional view on the lines 4-4 in Figure 1.

Figure 5 is a front elevational view of a machine of the conventional airplane type, showing an adaptation of this invention to 35 such a machine.

Figure 6 is a side elevational view of a machine of another type, showing the application of this invention to a stream-line frame.

Figure 7 is a front elevational view of the 40 invention, as illustrated in Figure 6.

Figure 8 is a front elevational view showing the application of this invention to a box frame type of machine.

Figure 9 is a plan view of the invention as 45 illustrated in Figure 8.

Like numerals of reference indicate corresponding parts in the various figures.

Referring to the drawings in Figures 1 to 4 the rotor frame indicated by the numeral 50 15 is formed of the upper parallel stringers

16 and the lower parallel stringers 17, spaced by the uprights 18 and the horizontal bars 19 and braced by the diagonal bars 20, thus forming frame sections.

The frame 15 is rigidly secured to and extends from the fuselage 21, in which a suitable motor is installed to drive the front propeller 22. The fuselage supports a motor 23 driving the helicopter 24, the shaft of which being journaled in the bearings 25 in the 55 centre of the frame 15.

The wind rotors 27 are arranged on either side of the helicopter 24 and extend in a transverse row in suitable number interrupted by said helicopter. The vertical wind 65 rotors 28 are mounted in the frame at the ends and rotated in vertical planes. The vertical wind rotors 28 are mounted in a transverse row interrupted by the fuselage and rotate in vertical planes transversely and thereby in 70 this type of the machine completing the arrangement of wind rotors and buoyancy members, the fuselage being supported on the carriage 29 as customary in airplanes.

In Figure 5 the adaptation of this invention is to an airplane of the bi-plane type and on the wing 30, the frame 31 of extended cone construction forms at the apex of each cone a bearing for each of the wind rotors 32, forming a transversely extending row of 80 wind rotors above the wing 30, rotating in horizontal planes. Between the wings 30 and 33 the vertical wind rotors 34 rotating in a vertical plane are supported in their mountings by the diagonal bars 35, while the 85 end wind rotors 36 are likewise mounted in the frame just beyond the wings and rotated in vertical planes in fore and aft directions. The fuselage 37 is suitably attached to the wings 30 and 33 and carries the motor driven 90 propeller 38, this fuselage being mounted on the carriage 39, as customary in flying machines.

In Figures 6 and 7 the numeral 40 indicates the stream-line frame tapering to a tail 41 95 and this frame carries the fore and aft row of wind rotors 42 interrupted by the central motor driven helicopter 43, which is here shown as driven by the motor 44 supported by the house 45 in the interior of the frame. 100

The bow propeller 46 is driven from the motor 47 contained in the forward house 48.

The wind rotors 49 are shown as mounted within the frame and turn in fore and aft directions in vertical planes, while the wind rotors 50 in the bottom of the frame turn in horizontal planes in transverse directions parallel to the planes of the wind rotors 49. The cabin 51 is shown as suspended from

10 the frame 40 for the crew and passengers.

In Figures 8 and 9, the numeral 52 indicates a box frame having the diagonal braces 53 supporting the bearings of several types of rotors. At the front of 15 the frame, the propeller 54 is driven by a motor contained in the house 55, while the helicopter 56 rotating in a horizontal plane is driven by a motor in the same house or thereabove. The wind rotors 57 and 58 respectively are mounted in the frame at the 20 top and bottom and rotate in horizontal planes, and on the sides the wind rotors 59 and 60 respectively rotate in fore and aft directions in vertical planes. The rudder 61 25 extends from this box frame 52 and completes the machine.

The frames as illustrated show different types of this flying machine and, of course, the frame may be round or it may be oval, 30 octagon, or otherwise according to the plans of the constructing engineer, so long as the salient features remain, namely the mounting of the wind rotors for rotation in vertical and horizontal planes as driving, buoyancy 35 and stabilizing members.

Further these buoyancy and stabilizing members may be used on hydroplanes or even on deep sea vessels for stabilizing purposes, but in the illustrations they are shown as applied to airships, though practically similar 40 applications may be made to other forms of ships.

The operation of a machine of any of the forms described and containing the same general 45 type of buoyancy, stabilizing and propelling members is obvious from the description of the details of the drawings, for the machine rises with the aid of the helicopter and the usual propulsion member and the 50 wind then lends a hand in the driving, floating and stabilizing of the machine, through the rotation of the several wind rotors.

What I claim is:—

1. In airship construction, a fuselage, 55 a frame extending from said fuselage and forming rotor bearings, a plurality of wind driven rotors rotatable in a horizontal plane and suitably journaled in said frame, a plurality of wind driven rotors rotatable in 60 vertical planes and suitably journaled in said frame, a central helicopter motor driven and supported from the fuselage and a motor driven propeller attached to said fuselage and forming the prime mover in the propul- 65 sion of the ship.

2. In airship construction, a frame work, a plurality of wind rotors rotating in a horizontal plane and a corresponding number in a parallel plane, fore and aft rotors rotating in parallel vertical planes, transverse rotors rotating in vertical planes, a lifting propeller and a propulsion member.

Signed at Montreal, Canada, this 26th day of December, 1928.

VICTOR AUGUSTE MARIE ERNEST BRAHY.
